UNITED STATES PATENT OFFICE.

AUBREY H. HARWOOD, OF LYNCHBURG, VIRGINIA, ASSIGNOR TO UNITED CIGARETTE MACHINE CO., INC., OF LYNCHBURG, VIRGINIA, A CORPORATION OF VIRGINIA.

MOUTHPIECE CIGARETTE WITH CRIMPED SEAM AND METHOD OF MAKING THE SAME.

Application filed March 29, 1922. Serial No. 547,694.

To all whom it may concern:

Be it known that I, AUBREY H. HARWOOD, a citizen of the United States, and resident of Lynchburg, in the county of Campbell and State of Virginia, have invented certain new and useful Improvements in Mouth-piece Cigarettes with Crimped Seam and Methods of Making the Same, of which the following is a specification.

10 The present invention relates to crimped mouth-piece cigarettes and the method of making the same and more particularly to mouth-piece cigarettes provided with a crimped seam extending over the body and 15 mouth-piece of the same; and has special reference to the making of such cigarettes in continuous rod form.

A principal object of my present invention relates to the making of crimped 20 mouth-piece cigarettes in continuous rod machines. In the standard form of cigarette rod machines a continuous cigarette rod is made by advancing a continuous web of cigarette paper onto which a tobacco 25 charge or filler is continuously fed, the paper after receiving its charge of cigarette filler being wrapped or rolled thereabout and fashioned into cigarette form, the edges of the cigarette paper being then secured 30 together as by pasting one of the edges and attaching the same to the opposite paper edge. After the cigarette rod is obtained the same is cut into cigarette lengths or units, each cigarette unit being provided 35 with a pasted seam. To comply with the demands of the trade in various localities and to eliminate various objections in the methods of manufacture of these pasted seam cigarettes it has long ago been proposed to 40 unite or secure the edges of the cigarettes with a crimped instead of a pasted seam. A common method of doing this consists in feeding the cigarette paper with its filler through a crimping mechanism usually con- 45 sisting of a small, finely knurled wheel over which the edges of the cigarette paper, folded into an interlocking seam, are moved, this small, knurled wheel operating in conjunction with a companion wheel or knurled 50 tongue to crimp the said seam. This crimping mechanism has been applied to the standard forms of continuous rod cigarette machines, the cigarettes obtained thereby being provided with a crimped, in lieu of a pasted seam.

Although cigarette machines of this type provided with crimping mechanism have been used to produce crimped cigarettes, the cigarettes so produced have, as far as I am aware, been always made "plain" as distinguished from cigarettes having mouth-pieces such, for example, as cork tips, a number of difficulties inherent in continuous rod crimping machines presenting themselves when the same is desired for making mouth-piece cigarettes. In making mouth-piece cigarettes such as cork tip cigarettes in continuous rod machines, mouth-piece or tipping sections are attached at spaced intervals to the advancing web of cigarette paper and the paper and attached mouth-piece sections are rolled or wrapped about the cigarette filler to provide a continuous cigarette rod. In making the rod in all prior machines of this latter type known to me the edges of the cigarette paper are joined by a pasted seam as distinguished from a crimped seam, the crimped seam being difficult of attainment in continuous rod machines equipped with tipping or mouth-piece attaching mechanism. After considerable experimentation I have found that one of the defects involved resides in the fact that in making the interlocking seam in the edges of the paper and tipping material for crimping purposes too many layers of the paper and tipping material are past between the knurled wheels, this presenting cumulatively too great a thickness of material for passage between the knurled companion wheels, resulting in a defective crimped seal. Another difficulty or defect that I have found lies in the tendency of the mouth-piece material such as cork to break or crack when folded into an interlocking seam. These and other disadvantages are present from an operating viewpoint when it is desired to use crimping mechanism with continuous rod tipping machines or tipping mechanism with continuous rod crimping machines.

After extensive experimentation to the end of meeting the demands of the trade in various localities for mouth-piece cigarettes having a crimped seam throughout, I have found that the standard cigarette rod machines may be provided with crimping and tipping mechanism and may be used in a manner for producing crimped mouth-piece cigarettes in which the defects and disadvantages

vantages above mentioned are successfully obviated. More specifically, I have found that the mouth-piece or tipping material may be so proportioned and arranged relatively to the cigarette paper to which it is attached that the multiple layers of added thicknesses of material at the seam of the cigarette may be eliminated, while at the same time the necessity for folding the tipping material is done away with and the breaking or cracking thereof accordingly obviated. A prime object of my present invention comprehends the employment of a method whereby these results may be secured and in which the making of mouth-piece cigarettes provided with a crimped seam throughout the length thereof including the mouth-piece of the same may be successfully accomplished.

20 To the accomplishment of the foregoing and such other objects as may hereinafter appear, my invention consists in the method and the article produced thereby, defined in the claims appended hereto.

25 In the drawings:

Figure 1 is a view showing the conventional steps used in the making of continuous rod cigarettes,

30 Figure 2 is a view showing the manner in which the tipping material is attached to the web of cigarette paper,

Figure 3 is an enlarged fragmentary perspective view showing the manner in which the cigarette paper is folded to provide the 35 seam and the seam crimped, this view being taken in cross section on the line 3—3, Figure 1,

40 Figure 4 is an enlarged fragmentary view with parts broken away of a completed cigarette made in accordance with my method,

Figure 5 is a cross sectional view thereof taken through the mouth-piece material, and

45 Figure 6 is a perspective view of a completed cigarette.

Referring first to Figure 1 of the drawings, I show in a conventional manner the various steps of making the cigarette rod and cutting the same into cigarette lengths or units. The web of cigarette paper 10 is unwound from a reel of cigarette paper 11 and is advanced through the various parts of the continuous rod machine, the said cigarette paper web being first moved past a tobacco charging or filling station 12, the tobacco filler 13 being here deposited in a continuous manner upon the advancing web of cigarette paper. Although I have illustrated in Figure 1 the depositing of the cigarette filler by showering the same on the cigarette paper, it will be understood that this showing is merely conventional, as my invention may be practised in the continuous rod machine of the pre-formed filler

type. During the feeding of the web of cigarette paper from the reel 11 to the tobacco filling station 12 the mouth-piece sections or tipping material are attached at spaced intervals to the underside of the said paper web. To this end I provide a tipping mechanism which is conventionally shown in Figure 1, the said tipping mechanism comprising means for advancing a web of tipping material such, for example, as a film 75 of cork 14 unwound from a reel 15, the said cork web being guided by the guide roller 16 and intermittently fed to a cutting drum 17 cooperating with a presser roller 18, these parts cooperating to feed the cork web and 80 cut the same into mouth-piece sections or units. The severed sections are then attached to the underneath of the cigarette paper 10 and to this end these sections such as 19 are passed between the presser roll 20 and the 85 presser cam drum 21, it being understood that the upper surface of the tipping material is suitably supplied with adhesive in any well known manner prior to feeding the same between the presser roll 20 and the 90 presser cam drum 21. With the provision of these means the mouth-piece sections 19 are attached at spaced intervals on the web 10 during the advancing movement of the latter.

95 For forming the cigarette rod the advancing web of paper 10 with the attached mouth-piece sections 19 carrying the tobacco filler 13 is moved through forming mechanism, the latter functioning to roll or wrap 100 the cigarette paper about the cigarette filler and to compress the filler to proper proportions as is well known in the art. This is diagrammatically and conventionally illustrated in Figure 1 and still referring to this 105 figure there is shown provided an endless belt 22 movable over the drum 23 and the roller 24, the said endless belt 22 functioning to grip and advance the web of cigarette paper with its filler through a forming 110 mechanism for forming the cigarette rod, the filler 13 being, during movement through the forming mechanism, subjected to suitable compression as by means of a compressing wheel 25. After the cigarette rod is rolled into the desired form the edges of the paper web 10 are then joined together and in the present form of my invention I provide the folding means 26 for folding the edges into an interlocking seam and the crimping 115 mechanism generally designated as 27 adjacent thereto, the said crimping mechanism serving to crimp the resulting folded seam. The crimping mechanism 27 is of a well known construction and comprises the 120 small, finely knurled crimping wheel 28 arranged on a suitable support 29 and the knurled wheel 30 cooperating therewith, the multiple layers of paper in the folded seam being passed between the knurled wheels 28 125 130

and 30 as is common in these devices, the seam being by this means crimped at both sides of the fold. The folded and crimped rod is then advanced to a cutting mechanism generally designated as 31, this cutting mechanism being of any approved type, comprising a cutting member 31' having a compound motion, the latter being movable in opposite directions longitudinally of the machine and oscillatably movable into cutting contact with the continuous cigarette rod 32, the cutting member 31' comprising the usual rotatable cutter. The cigarette rod 32 is moved through the guide 33 forming part of the cutting mechanism 31 as is well known in these devices, the cigarette rod 32 being severed into cigarette lengths or units 34 by means of this cutting mechanism.

As hereinbefore referred to, a principal object of my present invention relates to the making of crimped mouth-piece cigarettes by the continuous rod method as shown in Figure 1 of the drawings, in which the cigarette rod may be crimped throughout the length thereof including the mouth-piece material. For the purpose of successfully crimping the cigarette throughout its length I have found it highly desirable to join the cigarette paper edges and the edges of the mouth-piece material in such a manner as to reduce to a minimum the number of layers of paper and material passed between the crimped wheels of the crimping mechanism. To this end I have found it efficacious to so join the edges of the tipping or mouth-piece material as to have no part of the same form part of the interlocking fold of the cigarette paper edges. Moreover, I have found that the edges of the mouth-piece material may be joined without interlocking the same, no folds or bends being provided therein, breaking or cracking of the cork where cork is used for tipping material being thereby successfully prevented. To the accomplishment of these ends I proportion the mouth-piece material and attach the same relatively to the cigarette paper to provide or leave free marginal edges of the cigarette paper on both sides of the mouth-piece material, the marginal edges of the cigarette paper only being interfolded to provide the interlocking seam, the interfolding of these edges being obtained without interlocking or interlocking the edges of the mouth-piece sections. Referring to Figure 2 of the drawings, I show the manner in which the mouth-piece sections 19 may be attached to the cigarette web 10 to obtain the desired ends, and referring to this figure I show the mouth-piece sections 19 of a width smaller or less than the width of the cigarette web 10, the said mouth-piece sections being attached to the web 10 in a manner to provide the free marginal edges 35 and 36 in the cigarette paper. As an example it may be added that

the marginal edge 35 may be about 1 millimeter and the marginal edge 36 about 2 millimeters in width, the width of the cigarette paper 10 being about 25 millimeters. The marginal edge 36 is therefore made about 70 twice as wide as the marginal edge 35 to permit the desired interlocking, as will be clearer hereinafter.

By the provision of this method of attachment of the mouth-piece sections on the cigarette paper I am enabled to feed or advance the cigarette paper through and between the elements of the crimping mechanism for effecting a crimped folded seam in the cigarette paper, while preventing the 75 multiplication of layers of material in the mouth-piece sections, the latter forming no part of the cigarette fold, while at the same time permitting the crimping of the cigarette rod throughout its length, including 80 the mouth-piece material. This is shown more particularly in Figures 3 to 5 of the drawings, and referring to these figures, it will be seen that as the cigarette rod 32 is advanced and the edges of the cigarette paper provided with the folds such as 37 and 38 with these folds forming an interlock or a lock seam joint as clearly shown in Figures 4 and 5 of the drawings, the edges 39 and 40 of the tipping material 19 are brought 85 into butting or slightly lapping relation, no part of the tipping material being creased or folded or interlocked with the lock seam joint in the cigarette rod 32. Still referring to Figures 3 to 5 of the drawings, it will be noted that the tipping material 19 has been 90 so positioned on the cigarette web 10 that in the rolling and seaming of the cigarette rod the edge portion 39 of the tipping material, besides being disposed in slightly lapping relation with respect to the edge 40, is disposed directly over the lock seam joint provided in the cigarette paper. With this 95 form of arrangement the seamed cigarette rod is moved through the crimping mechanism to provide the crimp 41 in the folded seam of the rod and in the mouth-piece section 19, as clearly appears from a consideration of Figures 4 and 6 of the drawings. With this arrangement it will be noted that 100 only a single layer of tipping material is passed between the elements of the crimping mechanism and that the free edge 39 of the mouth-piece material is securely attached by 105 crimping to the crimped fold or seam of the cigarette paper. By the provision of this means and by providing the edge 39 of the tipping material in slightly overlapping relation with respect to the edge 40 thereof, I 110 am enabled to secure a very firmly attached 115 cork or other tip on the cigarette rod, while at the same time providing the desired crimp throughout the length thereof.

The practice of my method and the use 120 of continuous rod apparatus provided with 125 130

tipping and crimping mechanism for the obtaining of crimped mouth-piece cigarettes will, in the main, be apparent from the above detailed description thereof. It will be further apparent, as heretofore recited, that by the provision of my method I am enabled to successfully obtain mouth-piece cigarettes having cork or other tips provided with a crimped seam throughout the length of the cigarettes including the mouth-piece material. It will be further apparent that by the manner of attaching the mouth-piece material to the continuously advancing cigarette paper web in the practice of my invention not only may the edges of the paper web be securely connected in the desired crimped interlocking fold; but that the edges of the tipping material may be firmly attached to the crimped fold of the cigarette rod without subjecting the mouth-piece material to any breaking, cracking or splitting, the cigarettes obtained by my method having been found of uniformly good quality, the production thereof being effected with a minimum of "throw-outs".

While I have shown my device in the preferred form, it will be obvious that many changes and modifications may be made in the structure disclosed without departing from the spirit of the invention, defined in the following claims.

I claim:

1. A crimped mouth-piece cigarette having a wrapper and a mouth-piece section thereon, the lateral dimensions of the mouth-piece section being less than that of the wrapper for providing in the latter free marginal edges, the edges of the wrapper including the free marginal edges being folded in an interlock and the folds secured by a crimp, the said mouth-piece section having no portions infolded with the said interlock and the said crimp extending throughout the length of the interlock and over the mouthpiece section.

2. As a new article of manufacture, a crimped mouth-piece cigarette comprising a cigarette wrapper and a mouth-piece section thereon, the wrapper and mouth-piece section being crimped throughout the length of the cigarette.

3. As a new article of manufacture, a crimped seam cigarette having a mouth-piece comprising a cigarette wrapper having its edges folded to provide a lock seam joint and a mouth-piece section thereon having its edges in slightly lapping relationship, the said lock seam joint and mouth-piece being crimped throughout the length of the cigarette.

4. As a new article of manufacture, a crimped seam cigarette having a mouth-piece comprising a cigarette wrapper having its edges folded to provide a lock seam joint and a mouth-piece section thereon with its

edges forming a slight lap joint, the lock seam joint and mouth-piece joint being crimped throughout the length of the cigarette with the crimping on the mouth-piece extending over one layer only thereof and adjacent an edge of the same.

5. The method of making cigarettes which consist in advancing a web of cigarette paper having mouth-piece sections attached thereto at spaced intervals, in wrapping the same about a cigarette filler to provide a continuous cigarette rod, in folding the edges of the cigarette paper to provide a seam and in crimping the cigarette rod throughout its length, the crimping extending over the seam and mouth-piece section.

6. The method of making cigarettes which consists in advancing a web of cigarette paper having mouth-piece sections attached thereto at spaced intervals with the width of the mouth-piece sections less than the width of the paper web providing in the latter free marginal edges, in wrapping the same about a cigarette filler to provide a continuous cigarette rod, in folding the edges of the cigarette paper to provide a seam and in crimping the cigarette rod throughout its length, the crimping extending over the seam and mouth-piece section.

7. The method of making cigarettes which consists in attaching mouth-piece sections at spaced intervals to a web of cigarette paper, the width of the mouth-piece sections being less than the width of the cigarette paper for providing the latter with free marginal edges, in wrapping the paper and attached mouth-piece sections about a cigarette filler to form a continuous cigarette rod, in folding the free cigarette paper edges to provide a lock seam and in crimping the cigarette rod throughout its length, the crimping extending over the lock seam and the mouth-piece material.

8. The method of making cigarettes which consists in attaching mouth-piece sections at spaced intervals to a web of cigarette paper, the width of the mouth-piece sections being less than the width of the cigarette paper for providing the latter with free marginal edges, in wrapping the paper and attached mouth-piece sections about a cigarette filler to form a continuous cigarette rod, in folding the free cigarette paper edges to provide a lock seam, the wrapping and folding being such that the edges of the mouth-piece sections form a slightly lapped joint and in crimping the cigarette rod throughout its length, the crimping extending over the lock seam and the mouth-piece material.

9. The method of making cigarettes which consists in attaching mouth-piece sections at spaced intervals to a web of cigarette paper, the width of the mouth-piece sections being less than the width of the cigarette paper

- for providing the latter with free marginal edges, in wrapping the paper and attached mouth-piece sections about a cigarette filler to form a continuous cigarette rod, in folding the free cigarette paper edges to provide a lock seam, the wrapping and folding being such that the edges of the mouth-piece sections form a slightly lapped joint and in crimping the cigarette rod throughout its length, the crimping extending over the lock seam and the mouth-piece material, the crimping in the mouth-piece sections extending over one layer only thereof and adjacent an edge of the same.
10. In the method of making continuous rod cigarettes, the step of attaching mouth-piece sections at spaced intervals to a web of cigarette paper with the width of the former less than the width of the latter and with the mouth-piece sections attached to the paper web so as to leave free edge portions in the same on both sides of the mouth-piece section.

Signed at Lynchburg, in the county of Campbell and State of Virginia, this 27th 25 day of March, A. D. 1922.

AUBREY H. HARWOOD.
